FLANGED PLATE TIMBER CONNECTER

James E. Myer, Washington, D. C., and Arthur C. Horner, San Francisco, Calif., assignors to Timber Engineering Company, Washington, D. C., a corporation of Delaware

Application December 23, 1936, Serial No. 117,380

5 Claims. (Cl. 20—92)

This invention relates to timber connectors of the bolt and plate type and embodies a particular form of plate.

The installation and use of the present types of timber connectors present difficulties in the prefabrication and assembly of timber joints. It has been found impractical to insert connectors in grooves or embed them partially into the wood at the time of fabrication of the timber members due to the fact that such connectors project above the surface of the timber interfering with piling and storing of the prefabricated parts and the possibility of loss of the connectors. Where timbers are prepared in advance to receive connectors by grooving or the like changes in the moisture content of the wood will cause alteration of the grooves so that at the time of assembly the grooves must be recut before the connectors can be inserted.

It is an object of this invention to avoid these difficulties by the construction of a timber connector which will lie flush with the surfaces of the timber and be attached to said timber at the time of fabrication whereby to simplify the installation of connectors and to facilitate direction of the fabricated parts.

A further object of this invention is to decrease the slip at the joint under load and to increase the load carrying capacity of the bolt by a reduction of bolt deformation under load.

Referring to the accompanying drawings in which similar reference numerals indicate similar parts wherever used.

Figure 1 is a sectional view showing timbers connected by use of the device.

Figure 2 is a section on line 2—2 of Figure 1.

Figure 3 is a plan view of a different form of the invention.

Figure 4 is a section on line 4—4 of Figure 3, partly broken away.

Figure 5 is a plan view of still another form of the invention.

Figure 6 is a sectional view showing timbers connected by the form of Fig. 5.

Figure 7 is a perspective view of the bushing used in such modified form, and,

Figure 8 is an illustration of the location of stress in a simple bolted joint.

The numerals 9 and 10 indicate timbers to be connected by the present connector. Each of said timbers is provided with a bolt hole 11 and with said bolt hole 11 as a center is further prepared by recessing the abutting timber faces to present aligned grooves or seats 12 and further recessed between said seats 12 and the bolt hole

11 for a purpose hereinafter explained. These seats and the recess may be formed by an expansion bit and a grooving tool and a timber thus prepared is ready for the installation of the device as illustrated in Figures 1 and 2.

The connector comprises identical halves, each half being a circular plate 13 of suitable metal having a central bolt hole 14, a circumferential flange 15 and, in the constructions shown in Figures 3 to 6 a central hub and flange 16 surrounding the bolt hole. The plate 12 is formed with two or more nail holes 17, recesses 18 being provided for the reception of nail heads which seat therein.

In the form shown in Figures 5 and 6 the bore 15 of the hub 16 tapers inwardly as at 19 to receive a metal bushing 20 which tapers from a center of largest diameter 21 to form faces 22, 22, forming a double tapered bushing which is bored to form a central bolt hole 23.

In the manufacture of any of the forms of the connector plates in larger sizes the plate 13 may be made with openings as 24, Fig. 3 in desired number, reducing the weight of the connector with resultant saving of metal.

Referring to Figure 8 the stress in the wood under the bolt in a simple bolted joint in which no connector is present is concentrated at the edges of the timbers as shown by the shaded areas in said figure (Wood Handbook, September, 1935, United States Department of Agriculture, page 130).

In assembling a joint using the present form of connectors, the timbers to be joined are prepared as above described and the connectors seated with, in the case of the construction shown in Figures 1 and 2, the flange 15 entering the groove 12 and the plate 13 entering the recess prepared for it so that the outer face of the connector lies flush with the surface of the timber. While in this position nails 25 are inserted through the hole 17 and driven home so that the nail heads seat within the recesses 18. In this way the connector is attached to the timber without danger of loss and the connector presents no interfering surfaces above the surface of the timber.

The installation of the connector plates for the construction shown in Figures 3 to 6 is the same except that the timber has been additionally prepared for reception of the hub flange 16.

To complete the joint for the construction shown in Figures 1 and 2 the timbers are juxtaposed so that the bolt holes 11 are aligned and a bolt 26 having an upper washer 27 is inserted

through said holes and the connector plates, a washer 28 is applied to the bolt and the entire joint tightened by means of the usual nut 29.

In assembling the form of connector illustrated in Figures 5 to 7 the bushing 20 is placed in the seat formed in one of the plates by the inner wall of the hub 16 as shown in Figure 6 which leaves that portion of the bushing 20 above the median line 21 exposed. The other prepared timber is now placed in juxtaposition so that the bushing will be received by the other plate and seated within the hub 16. The usual bolt assembly described for the previous installation is now used and the joint tightened.

15 When it is desired to secure a timber to a metallic member the timber to be secured is fitted with one of the connector plates as described and bolted to the metallic member in the usual manner.

20 By reference to Figure 8 it will be seen that in a simple bolted construction the stress in the wood members joined together is concentrated at the edges of the timbers as shown. By the use of the present device this concentration of 25 stress is distributed by the plates to a much larger area of the wood than by using the bolt alone. Shear stress upon the bolt when used with the present timber connector is distributed by the flanges 15 over the wood in the case of the construction shown in Figures 1 and 2 and in the 30 constructions shown in Figures 5 to 7 is taken up not only by the flanges 15 but by the hub 16 and by the bushing retained within said hub. This distribution of stress increases the load carrying 35 capacity of the bolt by preventing the walls of the bolt hole from crushing at the points where the shear stress is most concentrated as illustrated by Fig. 8 thereby reducing its deformation under load and in the form of Figs. 5-7, due to the 40 action of the connector plates and bushing 20, transmits to the bolt a distributed and lessened shear stress solely.

45 As is well understood, bolted joints in timbers, without connectors, yield first by crushing of the fibers against the bolts. The bolts are thus deformed to a shape comprising laterally offset ends with parallel axes connected by a diagonal portion. The latter portion is subjected to a combined shear, tension and tearing action, most destructive upon the fibers of the metal.

50 In the forms of the present invention of Figs. 1-4, the bolt cannot crush the fibers of the wood, at least up to the limit of resistance against flanges 15. The stress upon the bolt is therefore 55 pure tension and pure shear at least until the washers 27, 28 sink into the wood and the flanges 15 crush the fibers. The bolt opening 14 is shown as rounded or chamfered where it meets the surface to be engaged by the remaining plate

so as to dull the shearing edges. It is obvious that this shear stress divorced from deformation of the bolt will be much less destructive of the bolt. The bolt hole 14 should fit the bolt rather closely.

5 In the form of Figs. 5-7 there is no shear upon the bolt until the flanges 15 crush the fibers of the wood and after this a shear will develop distributed between the points at the two ends of the bushing 20.

10 Minor changes may be made in the physical embodiments of the invention within the scope of the appended claims without departing from the spirit of the invention.

15 What I claim as new and desire to secure by United States Letters Patent, is:

1. A timber bond comprising juxtaposed timbers having coaxial grooves and recesses in the contacting faces thereof, a flanged plate seated in each timber and fitting said groove and recess, whereby said plates lie flush with the surfaces of the contacting faces of said timbers.

2. A timber connector comprising identical plates, each of said plates having a central bolt aperture, a flanged hub surrounding said aperture, a circumferential flange on said plate and a bushing engaging each of said flanged hubs when said plates are in connected relation.

3. A timber connector comprising a plate having a plane surface to lie flush with the surface of a timber and a central bolt opening, said plate formed with a peripheral flange projecting from its remaining surface, and extending completely thereabout.

4. A timber connector comprising a plate having a plane surface to lie flush with the surface of a timber, a central bolt opening dimensioned to closely fit a bolt to be used therewith, and having nail holes between said bolt opening and the periphery of the plate; the angle between said plane surface and said bolt opening cut away to delocalize the shearing stress upon a bolt in said opening; and an annular peripheral flange projecting from the remaining surface of the plate.

5. A timber connector comprising a pair of plates having plane surfaces in contact at the meeting plane of timbers to be connected, and having central registering apertures formed on frusto conical surfaces with opposed bases at said plane surfaces, each plate formed with an annular flange about said aperture and a peripheral annular flange projecting from its side opposite said plane surface, and a bushing having an axial bolt opening with its periphery formed complementary to the combined registering apertures in said plates.

JAMES E. MYER.
ARTHUR C. HORNER.
